(57) **CLAIM**

We claim the ornamental design for a hydraulic fluid tank, as shown and described.

DESCRIPTION

FIG. 1 is a perspective view of the design from a vantage point looking down upon the right front of the design.

FIG. 2 is a perspective view from a vantage point looking down at the right rear of the design.

FIG. 3 is a top plan view of FIG. 1.

FIG. 4 is a bottom plan view of FIG. 1.

FIG. 5 is a front elevation view of FIG. 1.

FIG. 6 is a left side elevation view of FIG. 1.

FIG. 7 is a right side elevation view of FIG. 1; and, FIG. 8 is a back elevational view of FIG. 1.

The hydraulic fluid tank is normally positioned on framework, for example, the framework of a vehicle, such that the bottom of the tank is normally not seen.
